Primary Examiner — T. Chase Nelson(74) Attorney, Agent, or Firm — Thompson Coburn LLP(57) CLAIM

The ornamental design for a footwear outsole, as shown and described.

DESCRIPTION

FIG. 1 is a perspective view of a footwear outsole showing the new design;

FIG. 2 is a bottom plan view thereof;

FIG. 3 is a medial side view thereof;

FIG. 4 is a lateral side view thereof; and,

FIG. 5 is a front view thereof.

The broken lines showing the remainder of the footwear and the tread pattern are for the purpose of illustrating environmental structure and form no part of the claimed design.
